US00D591350S

(12) United States Design Patent
Beyer

(10) Patent No.: US D591,350 S
(45) Date of Patent: * Apr. 28, 2009

(54) WRITING INSTRUMENT

(75) Inventor: Hans-Juergen Beyer, Ober-Ramstadt (DE)

(73) Assignee: Senator GmbH & Co. KGaA, Gross-Bieberau (DE)

() Term: 14 Years

(21) Appl. No.: 29/276,791

(22) Filed: Feb. 6, 2007

(30) Foreign Application Priority Data

Aug. 7, 2006 (DE) 4 06 04 137

(51) LOC (9) Cl. 19-06

(52) U.S. Cl. D19/50

(58) Field of Classification Search ..... D19/35, D19/36, 41-51, 53-57; 24/11 R, 11 F, 11 P; 401/52, 99, 100, 104-109, 192, 195, 196

See application file for complete search history.
